US0D1109072S

(12) **United States Design Patent** (10) Patent No.: **US D1,109,072 S**
(45) Date of Patent: ** Jan. 13, 2026

(54) **BATTERY**

- (71) Applicant: **ZEBRA TECHNOLOGIES CORPORATION**, Lincolnshire, IL (US)
- (72) Inventors: **Sunghun Lim**, Bethpage, NY (US); **Li-Ko Wang**, New Taipei (TW); **Chungwei Hung**, New Taipei (TW)
- (73) Assignee: **Zebra Technologies Corporation**, Lincolnshire, IL (US)
- (**) Term: **15 Years**
- (21) Appl. No.: **29/893,461**
- (22) Filed: **May 30, 2023**

Related U.S. Application Data

- (63) Continuation of application No. 29/698,753, filed on Jul. 19, 2019, now abandoned.
- (51) **LOC (15) Cl.** **13-02**
- (52) **U.S. Cl.**

Primary Examiner — Christy Nemeth

(57) **CLAIM**

The ornamental design for a battery as shown and described.

DESCRIPTION

FIG. 1 is a top perspective view of a battery;
FIG. 2 is a bottom perspective view thereof;
FIG. 3 is a top view thereof;
FIG. 4 is a bottom view thereof;
FIG. 5 is a left side view thereof;
FIG. 6 is a right side view thereof;
FIG. 7 is a front view thereof; and,
FIG. 8 is a rear view thereof.

1 Claim, 6 Drawing Sheets
